UNITED STATES PATENT OFFICE.

GEORGE J. D. TRETHEWEY, OF DETROIT, MICHIGAN.

FISHPLATE CLAMP.

Application filed January 12, 1925. Serial No. 1,906.

My invention relates to fish-plates and rail joints, and more particularly to boltless clamps for the same, by means of which the rails may be securely held in proper relation to each other and all creeping is prevented.

The object of the invention is to so construct the same that it will have but few parts, may be easily and cheaply manufactured, can be assembled with ease, and the parts composing the same may be repaired or restored with little labor.

In the drawings forming a part of this specification, and in which like symbols of reference represent corresponding parts in the several views:—

Figure 1 is a plan view of the device as the same appears assembled, or in its operative position;

Figure 2 is a transverse sectional view on the line 2—2, Figure 1;

Figure 3 is a perspective view of a portion of the plate showing slot in the same;

Figure 4 is a view of one of the pillar blocks, having a dove-tailed tongue to be received in the slot in the tie plate; and,

Figure 5 is a key to lock the pillar block.

In the drawings, 1 represents a set screw for locking the key 2 to the pillar block thus holding the latter in place. The key 2 has a plain surface on the side next the set-screw, the side next the pillar block is undercut, the side next the rail inclines inwardly at its base, and its outer or opposite side is undercut.

3 indicates the dove-tailed tongue of the pillar block, the same adapted to be received in the slot 6, and then slid into the portion 7 of the same. The slot 6 has its rail side inclined downwardly toward the rail, its key side plain, and its outer side flared or dove-tailed to agree with the configuration of the key 2.

4 indicates two locating pins adapted to be received in openings 8 in the pillar block 13, and openings 9 in the rails.

10 are lag screws to hold the plates firmly in place; and 11 a lag screw to fasten key 2 in place. The set-screw 1 is operated by means of a key with an angular end (not shown), as is usual in such cases. The opening 7 is undercut or dove-tailed to correspond with the tongue of the pillar block. 12 is the loose, and 13 the rigid, block.

55 The operation of the device will be apparent from the foregoing description.

When the device is in its operative position as shown in Figure 1, and the operator desires to disassemble the same, he will first loosen the set screw, then lift out the key, 60 then slide the pillar block with its tongue out of its seat into the key opening, when it may be withdrawn. The reverse operation is necessary in assembling the parts to make it once more operative. Of course it is not 65 necessary to use both screws 11 and 1 for key 2, one being sufficient, but either may be used, as desired. The tie plate, locking pins, and permanent pillar block, may if desired, 70 be made in one piece, or holes may be formed in the pillar block and the pins driven in the same. The pins hold the ends of the rails in place.

Having now fully described my invention, what I claim as new, and desire to secure by Letters-Patent, is:—

1. A rail joint, comprising a rigid block to engage one side of a rail, a tie plate formed with an opening having a reduced portion, a pillar block having a dovetailed tongue adapted to be received in the opening and slide within the reduced portion, and a key also adapted to be received in the opening to lock the pillar block tongue to the tie-plate.

2. A rail joint, comprising a tie-plate, a rigid, and a movable, pillar block engaging the same, a removable block having a dovetailed tongue, an opening having a reduced portion to receive the dovetailed tongue, and 90 a plurality of pins connected to the rigid pillar block and extending through perforations in the rails to hold the same.

3. In a device of the character described, a plurality of pillar blocks, one formed with 95 a dove-tailed tongue, a tie plate formed with an opening having a reduced portion which is undercut to receive the dovetailed tongue, and a key to be received in the enlarged portion of the opening to hold the tongue when 100 the same is slid into place.

4. In a device of the character described, a tie plate formed with an undercut perforation and an inclined side, a pillar block having a depending lug to engage and be locked in the perforation, and a key formed with two undercut sides and an inwardly inclined side to engage the perforation and be locked in the same.

In testimony whereof I affix my signature. 110

GEORGE J. D. TRETHEWEY.
